UNITED STATES PATENT OFFICE

2,576,398

ANIMATED TOY VEHICLE

George W. Harris, Drain, Oreg., assignor of one-half to John J. Konecny, Drain, Oreg.

Application June 7, 1950, Serial No. 166,599

1 Claim. (Cl. 280—1.175)

1

This invention relates to improvements in animated toys and more particularly to hobby horses of a size adapted to be ridden by children and to travel forwardly by forward and rearward rocking motion of the body of the rider of the hobby horse.

One of the principal objects of the invention is the provision of a toy of this character which is of simple, efficient, durable and inexpensive construction and which will simulate the action of a galloping horse as well as the sound of hoof beats thereof.

These and other objects will appear as my invention is more fully hereinafter described in the following specification, illustrated in the accompanying drawing and finally pointed out in the appended claim.

In the drawing:

Figure 1 is a side elevation of the toy in a starting position.

Figure 2 is a view similar to Figure 1 showing the body of the toy tilted rearwardly by the weight of the operator upon the seat to swing the forward legs of the toy forwardly.

Figure 3 is a view similar to Figures 1 and 2 showing the toy in an advanced position wherein the front leg has returned to the ground and the rear leg is free to swing forwardly.

Figure 4 is a view identical with Figure 1 showing the toy back in a starting position.

Figure 5 is an enlarged fragmentary sectional end elevation taken approximately along the line 5—5 of Figure 2.

Figure 6 is a sectional end elevation taken along the line 6—6 of Figure 1.

Figure 7 is a fragmentary end elevation taken approximately along the line 7—7 of Figure 3.

Referring now more particularly to the drawing:

In Figure 1 reference numeral 1 indicates the body of the horse which is made up of two panels 2 and 3 held apart in spaced relation to each other by attachment, by means of screws 4 or the like, to a central spacing element in the form of a single panel designed to represent the head, neck and front legs of a horse as generally indicated at 5. A second spacer block 6 is interposed between the rearward ends of the body member and secured thereto by means of screws 7. The forward end of the spacer block 6 is cut on an angle as indicated at 8 to form a limit stop for the rearward movement of the rear legs 9 of the horse. The upper end of the rear leg is pivotally attached to the body member near the upper edge thereof by means of a pin or shaft 10 about which

2

the rear leg 9 is swingably attached for forward or rearward movement with respect to the body 1. The pivot shaft 10 should be located forward of the center of a seat 11 secured to the top edge of the body member. The rearward swing of the leg 9 is limited by the angular surface 8 of the spacer block 6.

The bottom end of each front and rear leg 5 and 9 is provided with a base generally indicated at 12 and 13 respectively and as best illustrated in Figures 5 and 6, each base is made up of a horizontal block 14 transversely bored to receive a shaft 15 which is fixedly secured by means of a pin 16 to its respective leg. To each side of the block 14 I secure plates 17 and 18 which are of greater height than the thickness of the block and which serve to maintain the shaft 15 within the block 14. The plates 17 and 18 of the forward base are tapered rearwardly and the corresponding plates in the rear leg are tapered forwardly as best illustrated in Figures 1 to 4 inclusive.

It is to be understood that both bases are fixedly secured to the legs of the toy and that they do not rotate about the shafts 15. The body member 1 and the head, neck and front leg portion of the toy constitute one part and the rear leg 9 and its integral base 13 constitute another part which is swingably mounted to the body member as aforesaid. The forward end of the body of the toy may be swung from the starting position shown in Figure 1 to the position shown in Figure 2 by the operator leaning rearwardly upon the seat 11 by reason of the fact that the body member is pivoted about the pivot point 10. This rearward body movement of the operator will elevate the forward portion of the body member 1 as well as the neck, leg portion and block 12 thereof sufficiently so that the front leg and its base may be moved forwardly by the operator now leaning or rocking in a forward direction about the pivot point 10 which will lower the forward end of the body member causing a return of the front base 12 into contact with the ground. Then upon further forward movement of the body of the user the front base will assume the position shown in Figures 1 and 4 which will enable the rear leg 9 and its base 13 to swing forward into the starting position as shown in said Figures 1 and 4.

For the convenience of the operator in executing the forward and rearward rocking motions of his body, I provide a handle bar 19 extending through and secured to the head of the horse as illustrated in Figures 3 and 7.

While I have shown a particular form of embodiment of my invention, I am aware that many minor changes therein will readily suggest themselves to others skilled in the art without departing from the spirit and scope of the invention. Having thus described my invention, what I claim as new and desire to protect by Letters Patent is:

An animated toy of the character described comprising a body member made up of two spaced apart vertical panels, the rearward end of said panels being held in spaced relation to each other by a spacer plate interposed between said panels to also provide a limit-stop, the forward end of said panels being held in spaced relation to each other by a leg portion formed integral with a neck and head portion, said leg, neck and head portion being fixedly secured to said body member, a rear leg pivotally attached to said body member and swingable in the direction of the length of the body member between the said two panels and limited in its rearward swing by said spacer plate, a seat superimposed upon and secured to the top edge of said body member, said front and rear leg each being provided with a base of square box-like formation having vertical front rear and side walls, the forward bottom

edges of the side walls of the base for the front leg being of flat formation and the rear portion of the base for the rear leg being of flat formation to serve as limit-stops to prevent forward or rearward over-tipping of the body member, the rear portion of the base for the front leg being tapered rearwardly and upwardly and the forward end of the base for the rear leg being tapered forwardly and upwardly to form flat supporting surfaces for both of said bases when the bases are separated to their limit during operation.

GEORGE W. HARRIS.
